ALBERT M. WIGGINS, OF SHARON, PENNSYLVANIA, ASSIGNOR TO WESTINGHOUSE ELECTRIC & MANUFACTURING COMPANY, A CORPORATION OF PENNSYLVANIA

ELECTRICAL WINDING

Application filed January 17, 1931. Serial No. 509,383.

My invention relates to windings for electrical apparatus and particularly to multi-strand-conductor windings of the type used in transformers, reactors, and other similar devices.

In windings designed to carry currents sufficiently great to require a rather large cross-section of conductor, the losses from eddy-currents will be objectionably high if a single-conductor winding is used. Consequently, in such high-current windings, the conductor is usually sub-divided into a plurality of parallel-connected strands which are separately insulated to reduce the eddy-currents and the losses which result from them. It is highly important that the strands of such conductor be so arranged that the current will divide uniformly among them so that each strand may be fully loaded without overloading others. This result may be attained by so positionally transposing the strands that each strand has substantially the same resistance and reactance as does every other. It is to an improved solution of this problem of strand transposition that my invention is directed.

Generally stated, it is the object of my invention to provide a winding of such construction that local and eddy-currents may be reduced to a minimum, and the impedances of parallel paths may be made essentially equal.

More specifically, an object of my invention is to provide, for a winding of the parallel-path type a method of transposing the individual conductor strands or sections which permits, during the course of the winding, each section to occupy a position similar to that of every other section to thereby assure the desired equal-current distribution among all parallel paths.

A further object of my invention is to provide a scheme for accomplishing a transposition, of the character above mentioned, in which the change of position of the conductor sections is gradual, uniform and progressive throughout the entire winding.

Another object of my invention is to provide a transposition scheme which permits of a reduction to a minimum of the distortion in

coil shape which necessarily results at points where conductor sections are interchanged in position, and permits all coil turns to have a more nearly symmetrical contour than has heretofore been possible.

Other objects of the invention will be apparent from a description of a specific embodiment thereof, when taken in conjunction with the accompanying drawings, in which,

Figure 1 is a view, in sectional elevation, of a transformer of one type employing windings of the type to which my invention is particularly applicable.

Fig. 2 is a top plan view of a winding formed in accordance with my invention.

Fig. 3 is a view, in side elevation, of the winding of Fig. 2.

Fig. 4 is a sectional view, taken on line IV-IV of Fig. 2.

Fig. 5 is a developed view of the first or end turn of the winding of Figs. 2, 3 and 4.

Figs. 6, 7, 8, 9 and 10 are sectional views taken on lines VI-VI, VII-VII, VIII-VIII, IX-IX and X-X, respectively, of Fig. 5.

Referring to the drawings, I have shown, in Fig. 1, a transformer of a well known type comprising a core 10 and primary and secondary windings 11 and 12, which are of a type to which the transposition scheme of my invention may be readily adapted. In the remaining figures of the drawings, I have illustrated the constructional features of one of these windings, for instance, winding 11 of Fig. 1, the conductor of which is assumed to comprise a plurality of separate sections, to which I have applied my scheme for transposing conductor sections.

It will become apparent, however, as the explanation proceeds, that my transposition scheme is not exclusively limited to application in the windings of a transformer of the particular type shown, as it may, in addition, be applied to windings used in electrical apparatus of a wide variety of other types.

Referring to Figs. 2, 3 and 4, the winding there illustrated will be seen to be formed from a conductor comprising four parallel strands, separately insulated in the usual manner, and which I have designated by 1, 2,

3 and 4, respectively, in all figures of the drawings. The turns of the winding are wound about any suitable means of a central or other equivalent support, such as that indicated at 13. The two ends of the winding, to which connection with an external circuit may be made, are designated by the numerals 14 and 15, respectively.

The winding which I have shown comprises twelve turns of a four-strand conductor. In windings of a different number of turns, the same relative transpositions would be made at equal intervals. Also, for a different number of strands, a correspondingly different number of transpositions would be required to leave the strands at the two ends of the winding in the same relative positions.

In practicing my invention, in the preferred embodiment illustrated, I interchange the positions of one pair of adjacent conductor strands during the first turn of the winding, another pair during the next turn, a third pair during the succeeding turn, and so on through the complete winding, so that the original strand arrangement is returned to at the end of the final turn. Hence, during the course of the complete winding, each strand occupies a position similar to that of every other strand in the conductor.

I have found that a uniformly distributed twisting of the pair of strands positionally interchanged reduces the accompanying distortion of conductor shape to a minimum and permits all turns to have a symmetrical contour or shape. My transposition scheme makes use of such uniformly distributed twisting in the interchanging of strand positions.

Thus, as will be seen from Fig. 4, conductor sections 1 and 2, in proceeding from the beginning of the first turn, or point 14, to the opposite side of the coil, or point 16, in the winding, have been so twisted through an angle of 90 degrees that they assume the respective positions there shown, and, in further proceeding from point 16, through the succeeding half-turn, to point 17 in the winding, these same sections have been twisted through another 90 degrees, and their positions have thus been completely interchanged within the length of the first complete winding turn.

During the second or succeeding turn of the winding, which continues from point 17, conductor sections 1 and 3 are similarly interchanged in position, assuming the half-turned relation shown at point 18, and the completely interchanged relation at the end of that turn, or point 19. Similarly, in the third turn of the winding, starting from point 19, conductor sections 1 and 4 are positionally interchanged, intermediately at point 20, and completely at point 21.

During the fourth turn of the winding, ending at point 22, conductor sections 2 and

3 are similarly positionally interchanged, as are sections 2 and 4 in the succeeding turn, ending at point 23, sections 2 and 1 in the next turn ending at point 24, sections 3 and 4 in the turn ending at 25, sections 3 and 1 in the turn ending at 26, sections 3 and 2 in the turn ending at 27, sections 4 and 1 in the turn ending at 28, sections 4 and 2 in the turn ending at 29, and, lastly, sections 4 and 3 in the turn ending at 15, previously mentioned as completing the winding. It will be observed that the original arrangement of the conductor sections has thus been returned to at the end of this final turn.

It will be evident that, in thus progressing of three consecutive turns of the winding, the pair of adjacent strands positionally interchanged during any given turn is different from that of all other turns in the group and includes, with the exception of the first turn, one strand of the pair interchanged during the preceding turn. As will be seen, a similar relative selection and positional interchange of strand pairs is followed for all four groups of three consecutive turns each of which, in Fig. 4 of the drawings, respectively include the turns between points 14 and 21, 21 and 24, 24 and 27, and 27 and 15.

The twisting of the positionally interchanged strand pair through 180° need not take the whole turn length to accomplish, should it be desirable, from an electrical, manufacturing or other standpoint, to confine such transposition within some fractional part of the turn length. The drawings show utilization of the complete length of turn for this purpose because such modification better lends itself to explanation of the fundamental scheme involved.

It will be evident that, in thus progressing throughout the complete winding, which, in this case, has consisted of the twelve turns mentioned, each of the conductor sections 1, 2, 3 and 4 has occupied a position similar to that of every other section in the winding conductor, and, consequently, the total lengths of the sections are all equal. Since the positions have been shown to be similar, it follows that the reactances, as well as the resistances, of the parallel paths will likewise be equal, and the current distribution will thus assume the described balanced relation among the several conductor sections.

As will be seen from inspection of Figs. 5 to 10, inclusive, which illustrate, in a developed or unrolled form, the first turn of the winding included between points 14 and 17, the interchanging of the pair of adjacent conductor sections, sections 1 and 2, in case of this first turn, is accomplished, in the embodiment illustrated, by a gradual and uniform twisting which is distributed throughout the length of the complete turn. Thus, as illustrated at the half-completion of the turn or point 16, the sections 1 and 2 have

been twisted through 90 degrees to an on-edge position, and, at the point where the turn is complete or 17, these same sections have been further twisted through an additional angle of 90 degrees to assume a complete inter-changed position. The intermediate or 45 degree points are illustrated at 30 and 31, respectively, shown in section in Figs. 7 and 9.

10 Transposition of the adjacent sections 1 and 3 in the second turn is accomplished in an exactly similar manner, and, for the other pairs of adjacent sections in the succeeding turns, the method used is also that which has 15 been described for the first turn.

10 The advantage of this uniform twisting method of transposition, entirely apart from providing means to obtain the required uniform distribution of current already considered, lies in the small amount of distortion of, coil shape thereby produced, and is effective when the strand-pair interchange takes place in the exact or complete turn length or some fraction or multiple thereof.

25 This feature, as will be recognized, is an exceedingly valuable one, particularly in coils in which the maximum number of ampere turns must be crowded into a closely limited space.

30 It will be appreciated that, in using this method, a fixed relation is maintained between the number of sections in the conductor and the total number of turns in the complete winding. If, as has been illustrated, 35 one pair of adjacent strands is positionally interchanged during the exact length of each complete winding turn, to obtain complete transposition, the number of turns required equals the number of conductor sections in parallel, multiplied by a quantity equal to the number of sections less one; that is, if "n" designates the number of parallel strands, the number of winding turns "t" required to effect a complete transposition 40 is given by the expression "t" = "n(n-1)".

In the winding that I have shown and described, the number of turns required by this formula will be four multiplied by the quantity four minus one, or a total of twelve, 50 which, it will be observed, is the number illustrated.

It will be evident that, while I have shown, and so far described, the positional interchanging of a pair of strands by twisting through an angle of 180 degrees, as taking place within the exact length of a winding turn, there is nothing in my scheme, as has been mentioned, to prevent the use of some different relation between rate of twist and conductor length, should such be desired. For example, a pair of strands may be completely interchanged in progressing through some exact fraction or multiple "x" of turn length "l" instead of through the exact turn, 55 as has been so far considered. When such

modification is made, the relation between the number of conductor strands and total turns of the winding required for complete transposition becomes exceedingly flexible and no longer limited by the expression "t" = "n(n-1)", the expression applying to such modification being "t" = "n(n-1)x".

It will be further evident that, were a number of conductors "k", each having the construction shown in the drawings, to be wound side by side into a coil, the number of turns necessary to complete the transposition, on the basis of one strand pair per turn, would still remain twelve, in spite of the fact that the cross-section of the total conductor has been increased by the factor "k", because each of the "k" similar conductors could transpose its strands independently of the others or, in a parallel manner, as might be desired. By using such a parallel-conductor scheme, it is evident that the total turns required may, in many cases, be correspondingly reduced, and the application of my invention be thereby further broadened.

The relative dimensions of width to thickness of the individual sections now commercially used in multi-section conductors are such that they readily lend themselves to use in this transposition scheme, they being of the general order of two to one. It will be noted that such ratio, that is, a section width which is twice the thickness, has been illustrated in the drawings and it can be seen that these particular proportions give a minimum amount of conductor-shape distortion due to the twisting of the sections or strands. Other sizes of conductor section can, of course, be used with but slightly less advantage.

Although I have shown and described a certain specific embodiment of my invention, I am fully aware that many modifications thereof are possible. My invention, therefore, is not to be restricted except insofar as is necessitated by the prior art and by the spirit of the appended claims.

I claim as my invention:

1. In a winding for electric apparatus comprising a plurality of turns of conductor of "n" parallel strands, a system of strand transposition in which the adjacent strands of one pair have their positions interchanged by progressive twisting of the pair through an angle of 180° during an exact fraction or multiple "x" of turn length "l", a different pair of adjacent strands being thus positionally interchanged during each succeeding conductor length "xl" in such manner that, in progressing through "n(n-1)x" turns of the winding, the active lengths of all strands become substantially equal and each occupies a position similar to that of every other strand in the conductor.

2. In a winding for electrical apparatus comprising "t" turns of conductor having "n" parallel strands disposed concentrically

- with the axis of the winding, a system of strand transposition in which one pair of adjacent strands is twisted during the length of each complete turn of the winding through an angle of 180° to effect an interchange in the respective positions of the strands comprising said pair, said system being so developed that, in each group of " $(n-1)$ " consecutive turns of the winding, the pair of adjacent strands so positionally interchanged during any given turn is different from that of all other turns in the group and includes, with the exception of the first turn, one strand of the pair interchanged during the preceding turn, a similar selection and positional interchange of strand pairs being followed for all groups of " $(n-1)$ " consecutive turns, said groups being of such a number that the total turns " t " in the winding equals " n " multiplied by " $(n-1)$ ".
3. A winding for electrical apparatus comprising " t " turns of a common mean diameter wound from a conductor having " n " parallel strands of equal rectangular cross-section disposed in the winding concentrically with the axis thereof, in which one pair of adjacent strands is twisted during an exact fraction or multiple " x " of turn length " l " through an angle of 180° to effect an interchange in the respective positions of the strands comprising said pair, and in each group of " $x(n-1)$ " consecutive turns of the winding the pair of adjacent strands so positionally interchanged during any given conductor length " xl " is different from that of all other corresponding lengths in the group and includes, with the exception of the first length, one strand of the pair interchanged during the preceding length, a similar selection and positional interchange of strand pairs being followed for all groups of " $x(n-1)$ " consecutive turns, said groups being of such a number that the total turns " t " in the winding equals " n " multiplied by " $x(n-1)$ ".
4. In a winding for electrical apparatus comprising " t " turns of conductor having " n " parallel strands disposed concentrically with the axis of the winding, a system of strand transposition in which one pair of adjacent strands is twisted during an exact fraction or multiple " x " of turn length " l " through an angle of 180° to effect an interchange in the respective positions of the strands comprising said pair, said system being so arranged that, in each group of " $x(n-1)$ " consecutive turns of the winding, the pair of adjacent strands so positionally interchanged during any given conductor length " xl " is different from that of all other corresponding lengths in the group and includes, with the exception of the first length, one strand of the pair interchanged during the preceding length, a similar selection and positional interchange of strand pairs being followed for all groups of " $x(n-1)$ " consecutive turns, said groups being of such a number that the total turns " t " in the winding equals " n " multiplied by " $x(n-1)$ ".

ing followed for all groups of " $x(n-1)$ " consecutive turns, said groups being of such number that the total turns " t " in the winding equals " n " multiplied by " $x(n-1)$ ".

5. A winding for electrical apparatus comprising " t " turns of a common mean diameter wound from a conductor having " n " parallel strands of equal rectangular cross-section disposed in the winding concentrically with the axis thereof, in which one pair of adjacent strands is twisted during the length of each complete turn of the winding through an angle of 180° to effect an interchange in the respective positions of the strands comprising said pair, and in each group of " $(n-1)$ " consecutive turns the pair of adjacent strands so positionally interchanged during any given turn is different from that of all other turns in the group and includes, except for the first turn of the group, one strand of the pair interchanged during the preceding turn, a similar selection and positional interchange of strand pairs being followed for all groups of " $(n-1)$ " consecutive turns, which groups are of such number that the total turns " t " in the winding equals " n " multiplied by " $(n-1)$ ".

6. In a winding for electrical apparatus comprising " t " turns of conductor having " n " layers of parallel strands disposed concentrically with the axis of the winding, each of said layers including " k " strands disposed axially side by side, a system of strand transposition in which one pair of concentrically adjacent strands in each of the " k " axial-strand-layer divisions is twisted during each exact fraction or multiple " x " of winding turn length " l " through an angle of 180° to effect an interchange in the respective positions of the strands comprising said pair, said system being so arranged that, in each group of " $x(n-1)$ " consecutive turns of the winding, the pair of concentrically adjacent strands in each of the " k " layer divisions so positionally interchanged during any given conductor length " xl " is different from that of all other corresponding lengths in the group and includes, except for the first length, one strand of the pair interchanged during the preceding length, a similar selection and positional interchange of strand pairs being followed for all groups of " $x(n-1)$ " consecutive turns said groups being of such number that the total turns " t " in the winding equals " n " multiplied by " $x(n-1)$ ".

In testimony whereof I have hereunto subscribed my name this 13th day of January, 1931.

ALBERT MARCUS WIGGINS.
